UNITED STATES PATENT OFFICE.

WILLIAM J. MOORE, OF WASHINGTON, DISTRICT OF COLUMBIA.

SAFETY RAZOR.

Application filed January 6, 1925. Serial No. 890.

The object of my invention is to provide a construction of safety razor of the Gillette type which in what I now consider the most satisfactory embodiment of my invention combines the advantages of safety from risk of cutting the flesh without impairment of shaving qualities; of taking care of lather removed while shaving; of adjustment for close shaving; and of having the weight that is desirable in a razor. Of course, my invention may be embodied in forms in which all the named advantages may not be combined. My invention consists in whatever is described by or is included within the terms or scope of the appended claims.

In the accompanying drawings:

Fig. 1 is a perspective view with parts broken away the better to illustrate the construction of a safety razor embodying my invention;

Fig. 2 is a transverse section.

My invention as is usual with Gillette razors is embodied in a structure which includes the flexible LE blade, 10, the outer concavo-convex blade clamping plate, 11, the inner concavo-convex blade supporting plate, 12, which, however, has the special construction hereinafter described, and the detachable screw connected handle, 13.

The inner blade supporting plate, 12, is projected beyond each of the cutting edges of the blade being arched in a curve outward and downward and such arched portion is formed into teeth, 14, by parallel slits, and preferably the teeth at their ends are united by what in effect is a bar, 15, so that the skin or flesh is not engaged by the sharp teeth but by an extended smooth surface. Such bar, 15, has the further advantage that it adds desirable weight to the razor. However, I contemplate embodying my invention in a construction in which no bar will be used but the ends of the teeth will be free. At each end of the row of teeth is a similar arched finger, 16, these fingers being spaced apart a distance somewhat greater than the length of the blade edge so that the blade at the ends or corners will rest upon such fingers and not project beyond the same and hence the danger of cutting or gashing the flesh which exists when the end corners of the blade are exposed is avoided. Again as is clearly shown in Fig. 2 the blade edge engaging

surface of the finger, 16, is slightly higher than the adjacent surface of the teeth, 14, so that the entire edge of the blade from end to end is out of contact with the teeth and hence the entire cutting edge of the 60 blade is available for shaving. Of course, the degree of separation of the blade edge from the teeth while ample for the purpose stated is not sufficient to cause risk of cutting in shaving. The end fingers, 16, are 65 flexible or yieldable enough so that they may be bent up or down to regulate the space between the cutting edge of the blade and the teeth and thus enables adjustment of the closeness of the shave. If desired one 70 edge of the blade may thus be adjusted for a closer shave than the other edge of the blade and the razor kept permanently in that condition or there may be adjustment from time to time.

While my invention is preferably embodied in a razor of the Gillette type employing the double edge blade I, of course, do not limit myself to that embodiment.

The arched sides of the guard plate form 80 a pocket or basket to trap and hold the lather during shaving.

What I claim is:

1. A safety razor having a guard plate for the cutting edge of the blade, such plate 85 comprising blade supporting fingers at the ends, and teeth between such fingers, such fingers being joined to hold them from relative movement, and the end fingers being bendable independently of said intermediate 90 fingers in a direction transversely of the blade edge to vary the spacing of the edge from such intermediate fingers.

2. A safety razor as in claim 1 in which the end fingers are spaced from the adjacent intermediate fingers by a slot longer than the slots between adjacent intermediate fingers.

3. A safety razor as in claim 1 in which the intermediate fingers are joined at their 100 extremities by a continuous flesh engaging bar.

4. A safety razor as in claim 1 in which the length of the guard plate is greater than the length of the cutting edge of the blade, 105 and the blade at its ends rests in contact with the end fingers.

In testimony whereof I hereunto affix my signature,

WILLIAM J. MOORE.
